UNITED STATES PATENT OFFICE.

ALBERT NELSON, OF CHICAGO, ILLINOIS, ASSIGNOR TO THE AMERICAN BRAKE SHOE & FOUNDRY COMPANY, OF WILMINGTON, DELAWARE, A CORPORATION OF DELAWARE.

RETARDER.

Application filed May 10, 1926. Serial No. 107,844.

This invention relates to retarders which are used in railroad hump or gravity yards for controlling the movement of cars.

The retarder shoes which directly engage 5 the wheels of the cars are of sufficient length to engage one wheel for an appreciable period and more than one wheel at a time, sometimes being eleven feet in length. The customary installation comprises two shoes 10 disposed on opposite sides of each rail and arranged to engage the sides of the rim of the wheel under heavy pressure which is continued while the wheel or wheels are passing through the retarder. As a consequence 15 of the length of the shoe and the heavy pressure thereon and the travel of the wheel in contact with the shoe a waving action is imparted to the shoe and its support, which may at times be of relatively violent nature, 20 depending upon the speed of travel of the car and the structure of the walls and other conditions. The shoes are made of cast iron and they are mounted on a steel support and to avoid damage to the shoe and for other 25 reasons it has been customary to make the shoe in sections. But these sections have been made and secured to the support in a manner which has tended to weaken the sections and increase the liability of fracture, 30 which is highly objectionable for the reason that a broken shoe will most likely derail a car and damage the retarder.

The object of this invention is primarily 35 to improve the retarder shoe and the method and means for mounting it upon its support so that the sections of the shoe may yield bodily with the waving action of the support imparted to it by the car wheels without damaging the sections of the shoe 40 and without impairing the security of the fastening means.

A further object of the invention is to increase the strength of the retarder shoe as 45 a whole and of each of its sections, to simplify the installation of the shoe and the replacement of any section thereof, and to improve the specific fastening means whereby each shoe section is securely held upon its support and is capable of moving bodily 50 with the support and relatively to adjacent shoe sections.

And a further object of the invention is to secure the sections of a retarder shoe to the support by a single fastening means for 55 each joint formed by the adjacent ends of

a pair of shoes so that each shoe may move independently of its adjacent shoe while both shoes are still held securely upon the support.

Referring to the drawings:

Fig. 1 is a plan view of that part of a retarder unit which is arranged with a single rail.

Fig. 2 is a top plan view of a retarder shoe.

Fig. 3 is a front elevation of the retarder shoe.

Fig. 4 is an end elevation of the retarder unit part shown in Fig. 1.

Fig. 5 is a rear elevation of an end portion of the retarder shoe.

Fig. 6 is a sectional view on the line 6—6 of Fig. 5.

Fig. 7 is a rear elevation of an intermediate shoe section.

Fig. 8 is a sectional view on the line 8—8 of Fig. 7.

Fig. 9 is a detail sectional view of one form of the fastening means in which the head of the bolt is seated in a pocket closed at its sides.

Figs. 10 and 11 are detail views showing a pocket open on two sides.

Referring to the drawings 12 is a rail and 85 13, 13 are the retarder shoes mounted upon supports 14 in spaced relation on opposite sides of the rail. Each support extends in one piece throughout the length of the shoe and is conveniently made in angle form, as shown in Fig. 4. Springs 15 are interposed 90 between the shoe supports 14 and the buffers 16 which are mounted in rigid position, and guide rods 17 engage the shoe supports and the buffers to guide the shoe supports in their sliding movement relative to the buffers. 95

The shoe supports are caused to slide on wear plates 18 by sliding bars 19 which are engaged with the shoe supports and are operated by suitable means which it is not necessary to show or describe in detail. The 100 wear plates 18 are seated in the ties 20 which are not shown in Fig. 1, but one of which is shown in Fig. 4.

The shoe is made up of two tapered end sections 21 and a plurality of intermediate 105 sections 22 arranged end to end and mounted firmly and securely upon its support which extends integrally throughout the length of the shoe. A reinforcing back 23 is embedded in each section of the shoe and this back has 110

perforations 24 and may have dovetail recesses 25 to receive the cast iron body of the section for anchoring the body to the back.

The opposing ends of adjacent sections 5 are recessed to form a rectangular pocket 26 which has a circular extension 27, one-half of each being formed in each section so that when two sections abut end to end the two parts of the pocket will register and form a 10 complete pocket. A bolt has its head 28 seated in the rectangular pocket and its shank 29 seated in the circular extension, and this bolt passes through an opening in the shoe support and carries a nut 30. Thus 15 a single bolt is made to engage the abutting ends of two adjacent sections and the recesses in the sections necessary to receive the bolts are located in the ends of the sections where they will not weaken the sections. 20 Each end section is provided with a bolt pocket 31 adjacent its tapered end to receive a bolt for securing this outer end of the shoe to the support. That end of the back 23 in the end section which is located in the tapered end of the section is also tapered and is preferably cut away at 32, on opposite sides to form a point 33 which is bent down, as shown in Fig. 6.

Instead of making a closed pocket 26 I 35 may provide an open sided slot 34 to receive the head of the bolt, as shown in Figs. 10 and 11. The pocket in both forms, or in any other form in which it may be made within the scope of my invention, preferably 40 has its walls arranged to engage the head of the bolt to prevent the bolt from turning when a tool is used for applying or removing the nut.

The retarder shoes are adjusted, for operation, so close to the rail that the wheel entering between the shoes spreads them apart. The shoes are subjected to heavy pressures by the operating mechanism and also by the wheel and they are also subjected to severe 45 shocks and jars from the wheel and to considerable strain in service. When the wheel enters one end of the retarder between the two shoes it spreads the shoes apart at that end; the steel supports yield at that end to 50 permit the spreading, but the shoes do not spread and the supports do not yield beyond the area affected by the wheel. As the wheel travels through the retarder the area of the shoes and supports affected by the wheel also 55 travels. In this way a wave action is imparted to both shoes and supports. The supports being preferably made of steel will yield sufficient to accommodate this wave action, but the shoes are generally made of cast iron and provision must be made to prevent the shoes from fracturing under the wave action of the supports. This I have accomplished in a 60 simple manner by providing the fastening means for securing the shoe sections to the support at the joints between opposing ends

of adjacent shoes. Therefore, whatever movement there may be of one section relative to another will occur at the joints between the sections and not in the section itself. In this way each individual section is 70 capable of a limited bodily movement without liability of breaking. The steel back reinforces and strengthens the cast iron body of the shoe section and also holds the parts of the body together in event that it becomes 75 fractured so that the section may continue in use.

The provision of fastening devices at the joints reduces the number of fastening devices necessary to secure a shoe to the support and it locates the fastening devices where they will securely hold the sections on the support, but at the same time will permit a limited movement of one section relative to its adjacent section to prevent damage 80 to the shoe from the back pressure of the wheel as it progresses through the retarder, and notwithstanding such back pressure may be sufficient to produce a progressive yielding 85 of the support carrying the shoe. 90

Changes may be made in the form, construction and arrangement of the various parts of my invention and the shoe may be embodied in retarder installations of different kinds; and therefore I reserve the right 25 to make all such changes as fairly fall within the scope of the following claims:

I claim:

1. A retarder comprising a support and a shoe mounted thereon, said support being 100 continuous and capable of yielding in a wavy movement as a wheel travels in contact with said shoe, and said shoe being made in sections arranged end to end and secured to the shoe so that each section is capable 105 of a limited bodily movement independent of the other sections to conform with the wavy movement of the support.

2. The combination of a support, a retarder shoe comprising a plurality of sections arranged end to end, and means extending across and engaging opposing ends of adjacent sections for securing the sections to the support.

3. The combination of a support, a retarder shoe comprising a plurality of sections arranged end to end, and means located between and engaging opposing ends of adjacent sections for securing the sections to the support.

4. The combination of a support, a retarder shoe comprising a plurality of sections arranged end to end, said sections having openings at their opposing ends located partly in one section and partly in the other, 125 and bolts passing through said openings and engaging the supports for securing the sections to the support.

5. The combination of a support, a retarder shoe comprising a plurality of sec- 130

- tions arranged end to end, adjacent sections having a pocket formed in their opposing ends partly in one section and partly in the other, and bolts arranged in said pockets and engaging the support to secure the shoe to the support, walls of said pocket being arranged to engage the head of the bolt to prevent rotation of the bolt.
6. The combination of a support, a retarder shoe comprising a plurality of sections arranged end to end, adjacent sections having pockets at their opposing ends partly in one section and partly in the other, said pockets being rectangular in shape and having circular extensions, and bolts having their heads arranged in said rectangular pockets and their shanks in said circular extensions and engaging said support to secure the shoe thereon.
- 20 7. A retarder shoe comprising a plurality of sections arranged end to end, and a metal back embedded in the body of each of said sections, the opposing ends of said backs in adjacent sections being in abutting relation when the sections are arranged in a complete shoe.
8. A retarder shoe section comprising a body having a tapered end, and a metal back embedded in said body, the end of said back embedded in the tapered end of the body being tapered to conform with the body and turned inwardly at its point.
9. A retarder shoe section comprising a body having a tapered end, and a metal back embedded in said body, the end of said back embedded in the tapered end of the body being tapered to conform with the body and cut out at its sides, and the point between said cut outs being bent inwardly.

ALBERT NELSON.
